UNITED STATES PATENT OFFICE.

GEORGE M. TOURTELLOTTE, OF WORCESTER, MASSACHUSETTS.

DESIGN FOR AN ADVERTISING-STAND.

SPECIFICATION forming part of Design No. 25,922, dated August 11, 1896.

Application filed April 17, 1894. Serial No. 507,923. Term of patent 7 years.

To all whom it may concern:

Be it known that I, GEORGE M. TOURTELLOTTE, a citizen of the United States, residing at Worcester, in the county of Worcester and State of Massachusetts, have invented and produced a new and useful Design for an Advertising-Stand, of which the following is a specification, reference being had to the accompanying drawing, representing my new and original advertising device shown in front elevation.

In general appearance my design represents a platform, upon which is mounted a central supporting-stand having the similitude of a light-house, from which, near the top, extend a pair of horizontal arms upon opposite sides, the outer ends of said arms supporting a series of cards hanging pendent therefrom, with the upper card in said series attached to said horizontal arms and the lower cards in the series connected by flexible connections.

A denotes the platform or base, which is supported upon the telescopic standard B. Upon the platform or base A is the structure C, made in the similitude of a light-house, and from the sides and near the top of the structure extend the horizontal arms or bars D D, from which are suspended a series of cards E, the upper card in each series being attached to one of the horizontal bars at its central section and the cards in each series below the upper one being connected by flexible bands or cords.

What I claim is—

The design for an advertising-stand herein shown and described.

GEO. M. TOURTELLOTTE.
